CHEESE SERVER

Clayton A. Laughlin, Minneapolis, Minn., assignor to Arthur Salm Inc., Chicago, Ill., a corporation of Illinois

Filed Mar. 21, 1963, Ser. No. 74,078

Term of patent 14 years

(Cl. D44—29)

FIG. 1 is a perspective view of a cheese server showing my new design;

FIG. 2 is a top plan view thereof;

FIG. 3 is a side elevational view thereof; and

FIG. 4 is an end view thereof.

I claim:

The ornamental design for a cheese server, substantially as shown.
